US00D909998S

(12) **United States Design Patent** (10) **Patent No.:** **US D909,998 S**
Du (45) **Date of Patent:** **** Feb. 9, 2021**

(54) **EARPHONES**

(71) Applicant: **DONGGUAN PINMI ELECTRONIC TECHNOLOGY CO., LTD**, Dongguan (CN)

(72) Inventor: **Zhanyuan Du**, Kaifeng (CN)

(73) Assignee: **DONGGUAN PINMI ELECTRONIC TECHNOLOGY CO., LTD**, Dongguan (CN)

(**) Term: **15 Years**

(21) Appl. No.: **29/747,463**

(22) Filed: **Aug. 23, 2020**

(30) **Foreign Application Priority Data**

Apr. 9, 2020 (CN) 2020 3 0137470

(51) **LOC (13) Cl.** **14-01**

(52) **U.S. Cl.**

USPC **D14/223**

(58) **Field of Classification Search**

USPC D14/223, 205; D13/107, 108; D24/174; 455/90.3, 575.1, 569.1

Primary Examiner — Paula Allen Greene

(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective of the earphones where the earphones are received in a charging case. The broken lines in the drawings depict portions of the earphones that form no part of the claimed design.

1 Claim, 9 Drawing Sheets
